UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED METALLIC PLATE FOR RAILWAY CARS.

Original application filed May 16, 1925, Serial No. 30,777. Divided and this application filed November 2, 1925. Serial No. 66,269.

My invention relates to the construction of railway cars having parts formed of metallic plates which are subjected to lateral, buckling and sometimes torsional stresses. Said parts are made of one or more metallic plates or panels formed with vertical or horizontal corrugations or other integral stiffening or bracing means to resist such stresses. While efforts are made to block the lading in the car, the shocks caused by the heavy locomotives, the emergency air brake and the classification hump tear the lading away from its moorings and throw it against the end of the car, the lateral weaving of the car throws it against the side of the car, and the impact throws it against the bottom of the car. My invention is adaptable to box, gondola or other types of cars.

One of the objects of the invention is to provide metallic parts of a railway car which have great strength to resist the torsional and weaving stresses which exist in a railway car when moving in service. These stresses are caused by the inertia of the roof and superstructure when the train is suddenly stopped; rough or uneven tracks; the superelevation of the track on curves; the lateral inertia in rounding curves; eccentric thrust due to the lading being secured to one side of the car; the cars being "cornered"; the use of push pole pockets, etc. Such stresses rack and distort the superstructure which decreases the life of the car, and also causes the car to leak grain, sand, and other such material. Furthermore, such stresses cause leaky roofs and leaky and inoperative side and end doors.

The tendency of an all metal end wall to bulge is resisted partially by the corrugations, stiffening members or whatever means have been provided to transmit such stresses to the side wall or frame members of the car. Such tendency is also resisted by the corner post of the car acting as a vertical beam supported at its top and bottom and sustaining a horizontal load; in other words, the bulging of the end would pull the opposite corner posts toward each other. This bulging also tends to pull the end (or side) plate downwardly and the end (or side) sill upwardly. Another object of the invention is to reinforce or supplant the frame members against thrust perpendicular to their length by means forming a part of a corrugated or otherwise reinforced metallic end wall.

In the drawings:

Fig. 1 shows my invention applied to a box car.

Fig. 2 is a side elevation of Fig. 1.

Fig. 3 is a section on line 3-3 of Fig. 1.

Fig. 4 is a section on line 4-4 of Fig. 1.

Fig. 5 is an enlargement on line 5-5 of Fig. 1.

Fig. 6 is an enlargement on line 6-6 of Fig. 1.

Fig. 7 is an enlargement on line 7-7 of Fig. 1.

It has been proposed to press the central portion of a metallic plate (or plates) so as to form a continuous web or flange surrounding a panel and to reinforce this panel by horizontal corrugations or other integral reinforcements which traverse the panel and terminate adjacent the opposite portions of the web or flange. In such an arrangement the load upon the horizontal corrugations is transmitted to the continuous web for flange only through the intermediate means of the flat portion of the plate lying between the end of the horizontal corrugations and continuous web, or flange. It has also been proposed to press the central portion of a metal plate (or plates) so as to form a web or flange (supposedly) surrounding a panel and to reinforce this panel by horizontal corrugations or other integral reinforcements which are the same depth as the web or flange where they merge into it. In such an arrangement the web or flange as a beam is destroyed. In my construction the transverse corrugations destroy only a part of the value of the web, leaving a remaining portion which extends continuously around the panel to receive the stresses from the horizontal corrugations and to function as a beam and a stiffener. Such stresses are transmitted directly to the remaining portion of the web.

The corner post of an ordinary box or gondola car performs two functions; first, as a compression member of the truss forming the side frame of the car, and, secondly, as a vertical beam receiving the loads from the several horizontal frame members of the end wall and transmitting them to the side wall of the car. The end plate of a car is the end member of the roof framing struc-

ture and the end sill is the end member of the underframe and as such performs similar functions to the corner post. Also the end plate and the end sill are horizontal beams receiving the loads from the end wall and transmitting them to the roof structure and underframe, respectively. Therefore, in the specification and in the claims forming a part thereof the term "frame member" means either the corner post, end plate, end sill, side plate, side sill or any other similar frame member.

In my construction the transverse corrugations receive the impact thrust of the shifting load and transmit them to the surrounding corrugation which is preferably positioned adjacent the frame member or members. This surrounding corrugation may be designed to reinforce the existing frame member of a car or to co-operate with another part of the car to perform the functions of the frame member or may be designed to independently perform the function of the frame member and thus constitute the frame member itself.

In my construction the central portion of the metallic plate 1 (or plates 1-2) is pressed to form a continuous corrugation 3 surrounding a panel 4, which corrugation comprises an inner wall 5-6 and an outer wall 7-8 and is preferably positioned adjacent the outside edges of the plate or outside edges of the wall whether the wall is made of one or more plates.

The panel 4 is reinforced with corrugations 9 or integral ribs which traverse the panel and merge into a part of the opposite portions 5-5 of the inner wall of the continuous corrugation, leaving a remaining portion 10 of the inner wall which extends continuously and uninterruptedly on three (or preferably four) sides of the panel. The inner wall 5 receives the load from the transverse corrugations 9 and in combination with the outer wall 7 of the continuous corrugation forms a beam or a stiffener to prevent bulging in transmitting the load from the transverse corrugations to the car. The inner wall 5 and outer walls 7 of the vertical portion of the continuous corrugation are prevented from buckling or deflecting by being connected to the horizontal portions 6-8 of the corrugations by the (preferably) radial portions 11-12 which thus form a continuous or unending corrugation.

The transverse corrugations may be made the same depth or a greater depth than the depression forming the continuous corrugation but the corrugations are of less depth than the walls 5-5 where the merge into it.

Figs. 5-7 inclusive show a typical section through the floor, roof and side wall, respectively, and illustrate the construction wherein the surrounding corrugation 3 is positioned adjacent the perimeter of the wall of

the car and the adjacent part of the corrugation is formed to cooperate with the continuous corrugation and the extended flange to perform the usual functions of the respective frame members, thus eliminating the usual end sill, end plate, corner post, etc. The outer wall 7 of the continuous corrugation is preferably extended to form a flange 32 which is secured to the center sill 33 and floor sheet 34 and the floor sheet is flanged upwardly (35) and secured (36) to the corrugated end sheet. The floor sheet is secured to the corrugated sheet on both sides of the continuous corrugations so as to form a box girder construction which is very strong either as a beam or as a column.

Fig. 7 shows how a very similar box girder is formed by flanging the side sheet 37 and securing (38) it to the corrugated end wall. In the roof arrangement the end wall may be provided with an upstanding flange 39 corresponding to the usual roof sheet flange 41, which flanges are united by the usual cap 42.

While I have shown and described the corrugations positioned horizontally, it is understood that the corrugations may extend vertically or otherwise, and still come within the scope of the invention, and, furthermore, while I have described and claimed the wall made of "a plate", it is understood that it may be made of one or more united plates and still come within the scope of the invention.

This is a division of my co-pending application Serial No. 30,777, filed May 16, 1925.

I claim:

1. In a railway car the combination of a metallic side or floor sheet having a flange and an end wall comprising a metallic plate pressed to form a continuous corrugation surrounding a panel, said panel formed with transverse corrugations which merge into the opposite portions of the continuous corrugation, a portion of the outer wall of said continuous corrugation extended to form a flange secured to said sheet; said metallic plate secured to the flange of the sheet.

2. In a railway car the combination of a metallic side or floor sheet having a flange and an end wall comprising a metallic plate pressed to form a continuous corrugation surrounding a panel, said panel formed with transverse corrugations which merge into the opposite portions of the continuous corrugation, and are of less depth than the continuous corrugation where they merge into it, a portion of the outer wall of said continuous corrugation extended to form a flange secured to said sheet; said metallic plate secured to the flange of the sheet.

3. In a railway car the combination of a metallic side or floor sheet having a flange and an end wall comprising a metallic plate

pressed to form a continuous corrugation surrounding a panel, said panel formed with transverse corrugations which merge into the opposite portions of the continuous corrugation, a portion of the outer wall of said continuous corrugation extended to form a flange, said plate and sheet being secured together on opposite sides of the corrugation.

4. In a railway car the combination of a metallic side or floor sheet having a flange and an end wall comprising a metallic plate pressed to form a continuous corrugation surrounding a panel, said panel formed with transverse corrugations which merge into the opposite portions of the continuous corrugation, and are of less depth than the continuous corrugation where they merge into it, a portion of the outer wall of said continuous corrugation extended to form a flange, said plate and sheet being secured together on opposite sides of the corrugation.

5. In a railway car the combination of a metallic side or floor sheet having a flange and an end wall comprising a metallic plate pressed to form a continuous corrugation surrounding a panel, said panel formed with transverse corrugations which merge into the opposite portions of the continuous corrugation, a portion of the outer wall of said continuous corrugation extended to form a flange secured to said sheet; said metallic plate secured to the flange of the sheet; said sheet and end wall flange both secured to the longitudinal frame members of the car.

6. In a railway car the combination of a metallic side or floor sheet having a flange and an end wall comprising a metallic plate pressed to form a continuous corrugation surrounding a panel, said panel formed with transverse corrugations which merge into the opposite portions of the continuous corrugation, a portion of the outer wall of said continuous corrugation extended to form a flange secured to said sheet; said metallic plate secured to the flange of the sheet; said plate and sheet being secured together on opposite sides of the corrugation, said sheet and end wall flange both secured to the longitudinal frame members of the car.

7. In a railway car the combination of a metallic side or floor sheet having a flange and an end wall comprising a metallic plate pressed to form a continuous corrugation surrounding a panel, a portion of the outer wall of said continuous corrugation extended to form a flange secured to said sheet; said metallic plate secured to the flange of the sheet.

8. In a railway car the combination of a metallic side or floor sheet having a flange and an end wall comprising a metallic plate pressed to form a continuous corrugation surrounding a panel, a portion of the outer wall of said continuous corrugation extended to form a flange, said plate and sheet being secured together on opposite sides of the corrugation.

GARTH G. GILPIN.
